HOWARD MATRAVERS ASHLEY
By Francis Forbes

Attorney.

UNITED STATES PATENT OFFICE.

HOWARD M. ASHLEY, OF FERRYBRIDGE, COUNTY OF YORK, ENGLAND.

MACHINERY FOR MAKING GLASS BOTTLES, &c.

SPECIFICATION forming part of Letters Patent No. 403,718, dated May 21, 1889.

Application filed January 22, 1889. Serial No. 297,189. (No model.)

To all whom it may concern:

Be it known that I, HOWARD MATRAVERS ASHLEY, a subject of the Queen of Great Britain and Ireland, and a resident of Ferrybridge, in the county of York, England, have invented a new and useful Improvement in Machinery for Making Bottles and other like Hollow Glassware, of which the following is a specification.

This invention is additional to a series of improvements in processes and apparatus for making bottles and like hollow glassware by machinery, which I have set forth in previous specifications, forming part of an application for United States Letters Patent filed September 6, 1887, Serial No. 250,767, and divisions thereof, an application, Serial No. 290,512, filed November 10, 1888, and, more particularly, an application, Serial No. 292,766, filed December 5, 1888. The following description and claims are intended to be read in connection with the latter.

The present invention consists in certain novel combinations of parts, hereinafter set forth and claimed, all of which are adapted to be and are preferably embodied in a "repeating-machine," such as is set forth in my specification forming part of said application Serial No. 292,766.

The distinctive objects of the present invention are to shape the bodies of bottles and the like, or to finish the articles with greater uniformity of internal "gaseous pressure" and with less first cost and reduced running expenses as regards the means for inflating or expanding the glass within the shaping-mold.

This invention relates exclusively to the construction or organization of a peculiar "finishing mechanism" that operates by the exhaustion of the air from around a shaping-mold within which a hollow "parison" is suspended, and to the adaptation of the parison-forming "initial mechanisms" to coact with such "exhaust" finishing mechanism.

Two sheets of drawings accompany this specification as part thereof.

Figures 1 and 2 of the drawings represent sectional elevations of said exhaust finishing mechanism and corresponding sections through a coacting initial mechanism, illustrating their construction and operation as

parts of a bottle-making machine. Fig. 3 represents a plan of the parts below the line 3 3, Fig. 1. Fig. 4 represents a top view of a peculiar pipe-coupling shown in Figs. 1 and 2, and Fig. 5 represents an inverted plan of the head mold or collar shown in Figs. 1 and 2.

Like letters of reference indicate corresponding parts in the several figures of said drawings and those of the drawings forming part of said application, Serial No. 292,766, so far as like parts are shown.

A distinguishing feature of my said repeating-machine is a series of initial mechanisms, one of which is represented at A in Figs. 1 and 2, revolving in a horizontal plane and coacting successively with a finishing mechanism, Z, that is stationary or fixed in relation to them. Said initial mechanisms are conveniently carried by a horizontal disk or frame, E, which revolves beneath a relatively stationary top disk, L, and above a fixed base, I, carrying parts which coact therewith.

Each initial mechanism comprises a horizontal spindle, s, which determines its axis of rotation, bearings b b² therefor bolted to the disk or frame E, and a non-rotary disk, d, which is conveniently cast in one part with said bearing b; also, a nozzle, n, a two-part head mold or collar, c, a two-part parison-mold, m, and a vertical punch, p, that is axial relatively to said nozzle-collar and parison-mold, and is guided by the former; also, an inverting-frame, i, lateral slides s' s², carried by the latter and attached to the parts of said collar c and said mold m, respectively, and suitable devices whereby said slides s² are actuated by said disk d and said slides s' are actuated by an "opening-path" projecting from said disk L at the "delivering" side of the machine; also, a frictional wheel, w, or the like, keyed on said spindle s between said bearings b b², and actuated successively by "turning-paths" on the bottom of said disk L, to invert and revert said frame i and the parts carried thereby; also, locking-notches l l², or the like, which are conveniently formed in the periphery of said wheel w to coact with a detent, d', carried by said disk or frame E at each initial mechanism, and engaged by "unlocking-paths" on the bottom of said disk L immediately preceding said turning-paths. Parts above referred to and other accesso-

ries which are not shown in the drawings forming part of this specification are shown and more fully described in the drawings and specification of said application, Serial No. 292,766, 5 and form no part of the present invention.

The punch p , for the purposes of the present invention, is conveniently constructed with an air-passage extending from a contracted outlet-opening in its face to and 10 through the outer end or terminal, t' , of the punch, as shown in Figs. 1 and 2. Otherwise the initial mechanism and the remainder of the machine, excepting only the finishing mechanism, may be free from air-passages. 15 A great saving in first cost and in repairs may thus be effected. The T-piece t of the inverting-frame is conveniently made hollow to adapt it to coact with an inclosed stop-collar, c' , on the punch, for limiting the retraction 20 of the latter after its projection into the parison-mold, and to lighten the inverting-frame, and a stuffing-box, w^2 , on said T-piece is retained as a frictional guide for the punch, whereby it is kept from dropping in its position 25 represented in Figs. 1 and 2. A light spiral spring reacting against said terminal t' may take the place of the stuffing-box, if desired, or change its functions to those of a frictionless gland. The collar c is also pecu- 30 liarily constructed for the purposes of the present invention—that is to say, its parts are provided with corresponding equal segments of a horizontal true-plate, t^3 , Figs. 1, 2, and 5.

In the complete machine there are preferably 35 four stopping-points for the initial mechanisms, as regards their revolution—namely, a “casting-point,” where the parison is cast in inverted position, and on leaving which it is punched, reverted, stripped of the mold m , and paddled to regulate its elongation; a 40 “finishing-point;” a “delivering-point,” where the collar c is opened to release the finished bottle, and an “inverting-point,” at which the inverting of the frame i and the parts 45 attached thereto from the position in which they are shown in Figs. 1 and 2 is begun, so that at the casting-point each initial mechanism is locked by its detent d' with the punch p at bottom and the open end of the parison- 50 mold m at top.

As each initial mechanism approaches a stopping-point the revolving motion is suitably controlled by a brake, b^3 , having a handle within convenient reach of the operator 55 above the disk L , in which it is pivoted, and a lever-arm within the recess of the disk or frame E .

The rim of the latter is provided internally with stops s^4 at the respective initial mechanisms, and said lever-arm is provided with a terminal detent-cog to coact with such stops in succession. The revolving motion is thereby temporarily arrested when each initial mechanism reaches the finishing-point. The 65 initial mechanism here stands in the position illustrated by Figs. 1 and 2, directly above the finishing mechanism Z . This finishing

mechanism, as represented by Figs. 1 to 4, inclusive, comprises a coupling, c^4 , conveniently located within the base I at the finishing-point, with a vacuum-pipe, p^7 , leading thereto from an air-pump or other suitable exhausting apparatus. A plug, q^3 , occupies an alternative neck of said coupling, so that by simply transposing the plug and pipe the latter 70 may be carried down the central pillar of the machine and thence to the coupling, if preferred. To the top of said coupling c^4 a vertical pipe, p^8 , is swiveled, with a washer of anti-friction bronze between its fast collar 75 and the lower surface of the floor of the base, and a leather gasket beneath it. The swivel-joint is tightened by bolts, which draw the coupling upward toward the floor of the base. Above said floor the pipe p^8 is inclosed within 80 a hollow pillar, h^3 , provided with a drilled bushing, b^3 , near its lower end, and with an axial bore in its top, through which said pipe p^8 extends to a rigid air-tight elbow-coupling, c^5 , which connects thereto a bent pipe, p^9 . 85 The latter extends horizontally to the circle described by the reverted parisons as they hang from the collars c , and there extends vertically in a line with which the axes of the collars successively coincide at said finishing-point. 90 A vertical guide-rod, r^4 , is erected upon said coupling c^5 , and a cushioning-ring, r^5 , of elastic vulcanite, leather, or the like, is interposed between a lower collar of said coupling and the top of the pillar h^3 . The sides of a shaping-mold, m^2 , divided like said parison-mold m , are connected by laterally-swinging arms a^2 , having stop-hinges at their lower ends, to the stem b^4 of its bottom, which stem is cruciform, for example, in cross-section, so as to 100 slide within the bore of the pipe p^9 without materially obstructing it. The mold m^2 is thus supported by said pipe p^9 in vertical position. It is elevated to the position in which it is shown in Fig. 1, and simultaneously closed by 105 a vertically-moving vacuum-bell, v , which is provided internally with springs e , that engage with the backs of said arms a^2 and render the closure to a sufficient extent elastic. The true-plate t^3 , formed on the collar c and correspondingly divided, as aforesaid, coacts 110 with the top of the bell to render it sufficiently air-tight. A stuffing-box, w^3 , at the bottom of the bell renders its sliding junction with the pipe p^9 air-tight. The bell v is carried by a rigid arm, a^3 , overlying the horizontal portion of the pipe p^9 , terminating in the base of said stuffing-box w^3 at one end and guided by said rod r^4 at its other end. A gland, g , of anti-friction bronze, made fast 115 within a socket on said arm a^3 , embraces said rod r^4 , and is provided with a spline which occupies a longitudinal groove in the rod to resist torsional strains.

In erecting and aligning the finishing mechanism the arm a^3 and the pipe p^9 , together with the parts which they carry, may be turned together on the axis of the vertical pipe p^8 without strain, owing to said swivel-

connection between said pipe p^8 and the coupling c^4 ; or the latter may be turned to align it with the pipe p^7 , and provision may be made for adjusting the whole mechanism, except its foot-lever, radially or toward or away from the center of revolution by a slot at s^8 in the floor of the base I . After alignment, the only movements of the finishing mechanism proper are the vertical movements of said 5 arm a^3 and the parts carried upward thereby. These portions of the finishing mechanism are raised and lowered by a foot-lever, f , and connection c^6 between the same and the splined end of the arm a^3 . To facilitate their 10 elevation, the heavy vacuum-bell v is wholly or in part counterbalanced by a weight, w^2 , suitably connected therewith, as by a forked lever, f^2 , having a central fulcrum at the upper end of a rigid arm, a^4 , which springs from 15 the pillar h^3 and coupled at its forked end to the ring which incloses the gland g of said 20 arm a^3 .

The operation of said finishing mechanism Z is as follows: The initial mechanism A having 25 reached the finishing-point and being there held in position by the brake and detent b^3 , with a parison depending from its collar c and ready for the shaping-mold m^2 , the operator depresses the foot-lever f and 30 thereby elevates the vacuum-bell v and the mold m^2 , the latter in the condition represented in Fig. 2, until the neck end of the mold strikes the face of the true-plate t^3 . During this first part of the movement of the 35 bell the mold is carried largely upon the springs e . As its movement continues, the resistance of the springs is overcome and the inclines formed by the flaring upper end of the bell, acting together with the springs, 40 upon the arms a^2 , close the mold, so that its neck embraces the depending ring of the collar c and becomes coupled thereto. Finally, the springs acting alone hold the sides of the 45 closed mold together and the upper edge of the bell closes sufficiently air-tight against its seat, which may preferably be sunk into the face of the true-plate, as shown. The parts now appear as represented in Fig. 1. The 50 closed bell v being in communication with the vacuum-pipe p^1 through the pipes p^8 and p^9 , a partial vacuum is immediately created therein and in the mold m^2 inclosed thereby, thus expanding the parison against the side 55 walls and bottom of the mold, so as to finish the bottle, its head having been formed by casting and punching in the act of making the parison. The bell v is then lowered, and when 60 the springs e pass below the straight portions of the arms a^2 the mold drops open by gravity. The bell and mold are then lowered together to their normal position of rest represented in Fig. 2, so as to clear the finished bottle and the slides s^2 , which carry the parts 65 of the parison-mold.

In the operation of so expanding the bottle by exhausting the air from around the parison and during the retraction of the punch p

after the preliminary parison-forming operation, the air which flows through the punch into the interior of the parison under atmospheric pressure is advantageously heated by contact with the hot metal, so as not to chill the glass. As soon as the bell v is fully lowered, the brake b^3 is pushed back and the revolving motion of the initial mechanisms 70 is resumed, which carries the bottle by its head to the delivering-point, where it is released by opening the collar c , as aforesaid, having become sufficiently rigid in transit.

With the finishing mechanism Z constructed as represented in Fig. 1 and by full lines in Fig. 2 the vacuum apparatus may 80 create a pulsating exhaust, the sound of which would enable the operator to correspondingly time the elevation of the bell v .

Alternatively the pipe p^7 (or the pipe p^8) 85 may be provided with a suitable valve, as v^2 , operated by a conveniently-located hand-lever, h^5 , through suitable connections, c^5 , as represented by dotted outlines in Fig. 2.

I have shown and described my present improvement as embodied in a repeating-machine. It may also be embodied in part in a "single" machine such as is set forth in my previous specification forming part of said 95 application, Serial No. 290,512, and for making large-mouthed bottles or jars and the like the duplex punch described in the latter would be preferred. Other like modifications will suggest themselves to skilled machinists, 100 and I do not limit my respective claims, hereinafter stated, to mechanical details, except as therein expressly set forth.

I disclaim, as forming no part of my present invention, all parts, combinations, and 105 processes hereinbefore incidentally specified or mentioned that are described and shown in my aforesaid previous specifications and drawings.

Having thus described and defined my present improvement, I claim as my invention and desire to patent under this specification—

1. In a machine for making bottles and other like hollow glassware, the combination, with a vertically-sliding vacuum-bell, and a 115 divided collar adapted to suspend a hollow parison by its head, and provided with a correspondingly-divided true-plate opposed to the upper end of said bell, of a shaping-mold within said bell, comprising a bottom having 120 a longitudinally-movable stem, and laterally-swinging sides carried by arms which are hinged to said stem, substantially as hereinbefore specified.

2. In combination with a collar adapted to 125 suspend a hollow parison by its head and provided with a horizontal true-plate, a self-opening shaping-mold fitted to said collar at its neck end and comprising a bottom having a longitudinally-movable stem and laterally- 130 swinging sides carried by arms which are hinged to said stem, and a vertically-sliding vacuum-bell, to close and inclose said mold, having internal springs and inclines which

coact with said arms, substantially as hereinbefore specified.

3. The combination of an initial mechanism for making hollow parisons in inverted 5 position, reverting them and suspending them by their heads in succession, which travels in a longitudinal plane and comprises an invertible parison-mold and head-mold or collar, the latter provided with a true-plate, and 10 a relatively stationary finishing mechanism which comprises a vertically-movable shaping-mold which is normally open and lowered so as to clear the depending parisons, their molds, and the supports of the latter, and a 15 vacuum-bell which elevates and incloses the shaping-mold and itself closes against said true-plate, substantially as hereinbefore specified.

4. The combination, substantially as hereinbefore specified, of the vacuum-pipe p^7 , the

swivel-coupling c^4 , the vertical pipe p^8 , the elbow-coupling c^5 , the bent pipe p^9 , and the vacuum-bell v , the latter having a stuffing-box fitted to the vertical end of said pipe p^9 , whereby provision is made for adjusting and 25 working the bell without straining the airtight joints.

5. The combination, with the vertically-movable vacuum-bell v and relatively stationary vacuum-pipe p^9 , of the arm a^8 , having the 30 stuffing-box of the bell at one end and an anti-friction gland at its other end, the guide-rod r^4 , foot-lever f , counterbalance-weight w^2 , and suitable connections between said arm and said lever and weight, respectively, substantially as hereinbefore specified.

H. M. ASHLEY.
